UNITED STATES PATENT OFFICE.

FREDERICK JOHN CHAMBERS, OF LONDON, ENGLAND, ASSIGNEE TO AUTOMATIC TELEPHONE MANUFACTURING COMPANY LIMITED, OF LIVERPOOL, ENGLAND.

TRANSMITTER FOR SIGNALING BY ELECTROMAGNETIC WAVES

1,194,274.

Specification of Letters Patent.

Patented Aug. 8, 1916.

Application filed October 31, 1914. Serial No. 869,674.

To all whom it may concern:

Be it known that I, FREDERICK JOHN CHAMBERS, a subject of the King of Great Britain, residing in London, England, and whose post-office address is 4 Princes Square, London, England, have invented a certain new and useful Improved Transmitter for Signaling by Electromagnetic Waves, of which the following is a specification.

10 In my co-pending application, Serial No. 676,190, I have described an arrangement for producing highly damped oscillations for signaling by electromagnetic waves in what are known as "shock" or "impact" excitation methods. In this previous specification a multiple series spark gap system was shown in which each individual spark was formed between non-parallel surfaces closely adjacent, maintained substantially 15 at a constant distance apart, the said surfaces comprising on the one hand a set of conducting disks of large heat capacity secured to but insulated from a rotating shaft, and on the other hand stationary disks 20 mounted on spindles parallel to the rotating shaft. According to the arrangement the current passed from a stationary disk to a closely adjacent moving disk, from the latter to a stationary disk and so on.

25 In the arrangement according to the present invention, two similar sets of conducting disks are secured to but insulated from shafts rotating about parallel axes, so arranged that a small air gap separates the 30 peripheries of opposite disks of the two sets. The current passes alternately from a disk of one set to a disk of another throughout the series.

Figures 1 and 2 are respectively a plan view 40 and elevation of a construction according to the invention, in which a' are metallic disks rotating with the spindle b' but electrically insulated from it by the insulating sleeves c' . The disks a' are of the form shown 45 in which the end plates are single disks provided with slip rings d for conveying current from and to the brush terminals e and the remaining disks are broader and formed with projecting flanges. A second set of metallic disks a^2 similarly formed with pro-

jecting flanges are mounted on spindles b^2 and insulated by insulating sleeves c^2 . The arrangement is such that both sets of disks can be set in rotation by the pulleys h' and h^2 , or only one set; if both sets are in rotation the spindles must revolve in the same direction, so that adjacent portions of the peripheries of the two sets of disks are moving away from each other. The flanges on the disks serve as electrodes between which the sparks pass, so that the discharge passes from one terminal e across air gaps between the flanges of the disks a' to the flanges of the disks a^2 until the slip ring connected to the other terminal e is reached.

55 The length of the spark gap can be adjusted by moving one set of disks a^2 toward or away from the other set a' . In the example shown this is effected by arranging the supports f of the spindle b^2 , so as to slide 60 in the fixed standards g^2 . Springs m attached to the supports f and abutting against the fixed standards g' supporting the disks a' press the movable supports f 65 against an adjustable set screw k . The disks can be clamped in the position set by means of the locking levers l . It is obvious that any other suitable device might be employed 70 for adjusting the position of the movable disks. The number of the disks and consequently of the spark gaps in series can be 75 altered, when it is found advisable.

Having thus described my invention and the best means I know of carrying the same into practical effect, I claim:

80 In the transmission of wireless signals, a transmitter comprising two sets of conducting disks of large heat capacity, respectively secured to but insulated from rotatable shafts, the axes of the shafts being parallel, 85 and the peripheries of the disk of one set being adjacent those of the other set to form a plurality of spark gaps in series with each other, each having as one electrode a disk of one set and as the other electrode an 90 oppositely disposed disk of the other set.

95 FREDERICK JOHN CHAMBERS.
